Thos. D. Brown
HIS ATTORNEY

UNITED STATES PATENT OFFICE.

LEROY J. BUTTOLPH, OF GRANTWOOD, NEW JERSEY, ASSIGNOR TO COOPER HEWITT ELECTRIC COMPANY, OF HOBOKEN, NEW JERSEY, A CORPORATION OF NEW JERSEY.

THERAPEUTIC LAMP.

Application filed November 29, 1924. Serial No. 752,996.

My present invention relates to a source of ultra-violet light for therapeutic uses and particularly to such a source adaptable for local and more or less continued application.

5 It further relates to method and means in such a device for applying pressure or dehematizing the tissue to be treated with the ultra-violet light.

In the drawing which is a part of this application is shown in vertical section the source of ultra-violet light of my invention as applied to an arm for example showing means for applying pressure to the part to be treated, means for varying exposure area, 15 and means for cooling the light source.

In the drawing the jacketed lamp casing 1 is held to the arm 2 by means of the straps 3, the window portion 5 of the lamp being held by said straps 3 to that portion of the 20 arm to be treated. Said window portion 5 comprises an iris diaphragm which is collapsible and openable for the purpose of varying the exposure area, the device being held by said straps 3—3 or equivalent means 25 to the part to be treated in such a manner that the boundary of the opening 6 of said iris 5 is held tightly against the tissue surrounding the part to be treated. The insulated members 8—8 pass through the jacket 30 wall of the container 1 and carry there-through the terminal leads 9—9 which end in suitable electrode terminals 10—10 properly spaced from each other within said casing 11. The inlet pipe 12 and the outlet pipe 35 13 serve to admit cooling material such as water to and from the jacket of the casing 1. The pipe 15 passing entirely through the casing 1 and opening into the interior thereof serves to admit hydrogen into the interior of said casing 1 and against the tissue to be treated for the purpose of dehematizing. The gauge 16 on pipe 15 serves to indicate the pressure applied to the tissue to be treated.

45 In the use and operation of the device of my invention the lamp casing 1 is attached to the part to be treated as by means of said straps 3—3 under the proper tension and pressure and a cooling liquid is started circulating through the jacket thereof by means of said pipes 12 and 13. Pressure is then applied to the part to be treated by admitting hydrogen for example into the interior 50 of the casing 1 which at the opening 6 is

bounded by the tissue to be treated. The 55 lamp casing 1 being held against the tissue to be treated by said straps 3—3 or equivalent means it is possible to obtain a practical holding of the hydrogen under pressure in the lamp casing against the part to be treated. Current is then applied to the leads 9, 9 of the electrode 10, 10 from a suitable source for the producing of an arc for the production of ultra-violet light, the hydrogen being a transmitter of ultra-violet light and 65 also serving as means for insulating the part to be treated from the heat of the arc.

In the apparatus and method of my invention I employ the atmosphere, hydrogen for example, as a suitable medium in which 70 to generate the ultra-violet light producing arc, as means for applying pressure to the part to be treated, and as a cooling medium. In some cases I use the hydrogen for cooling without employing the medium such as 75 water in the casing jacket. Flow of hydrogen when desired to secure the desired cooling effect I produce by permitting the hydrogen to escape around the edges of the opening 5 or when desired or required I provide 80 another pipe for its exit.

I claim:

1. A therapeutic apparatus including a holder member having an aperture for application to the part to be treated, a source of ultra-violet light within said holder and means for applying a gas under pressure to the part to be treated at the area confined by said opening.

2. A therapeutic apparatus including a 90 holder member having an aperture for application to the part to be treated, a source of ultra-violet light within said holder and means for applying a gas under pressure to the part to be treated at the area confined 95 by said opening, and means for cooling said casing.

3. In a therapeutic appliance a jacketed casing, inlet and outlet paths for distributing cooling fluid through the jacket of said casing, a source of ultra-violet light in said casing, an opening in said casing, and a pipe to the interior of said casing.

4. In a therapeutic appliance a jacketed casing, inlet and outlet paths for distributing cooling fluid through the jacket of said casing, a source of ultra-violet light in said casing, an opening in said casing, an iris

diaphragm across said opening, and a pipe to the interior of said casing.

5. A therapeutic apparatus including a holder member having an aperture for application to the part to be treated, a source of ultra-violet light within said holder and means for applying a gas under pressure to

the part to be treated at the area confined by said opening, and adjustable means for varying the size of said opening.

Signed at Hoboken in the county of Hudson and State of New Jersey this 28th day of November A. D. 1924.

LEROY J. BUTTOLPH.
